8 Claims. (Cl. 176—1)

This invention relates to high temperature plasmas and means for heating and confining high temperature plasmas.

Since the advent of thermonuclear research and development it has been desirable to heat and confine high temperature plasmas. One approach to this problem has been the stellarator in which the plasma has been heated and confined in an endless discharge tube by means of an externally imposed magnetic field.

In the stellarator described in U.S. Patent 3,015,618, a plasma of ions and electrons has been ohmically heated in a cylindrical column while an externally imposed axial magnetic confining field with a rotational transform has confined the heated plasma inside the discharge tube with a substantially uniform density gradient across the heated plasma diameter and substantially without rotation of the heated plasma as a whole around the tube. Also, the heated plasma has been neutrally charged throughout its cross-section and there has been a substantially uniform diffusion coefficient across the heated plasma.

It has now been discovered that by properly positioning an exposed electrical conductor deeply into the heated plasma, impressing a large positive potential on this conductor relative to the discharge tube, and by drawing a large electron current through this conductor to disturb the charge neutrality of a particular portion of the heated plasma, an internally imposed, strong, annular radial electric field region is established in the whole outer region of the heated plasma which is reacted with the externally imposed axial magnetic confining field rapidly to rotate the heated plasma portion in the electric field region, thus greatly to decrease the loss rate of the heated plasma to the discharge tube wall.

Various other advantages will appear from the following description of one embodiment of this invention, and the novel features will be particularly pointed out hereinafter in connection with the appended claims.

In the drawings, where like parts are numbered alike:

FIG. 1 is a partial isometric view of a high temperature stellarator having an endless discharge tube, external magnetic means, and means for positioning the electric field producing conductor of this invention in the stellarator tube;

FIG. 2 is a partial cross-section of the discharge tube of FIG. 1 showing the intersection of magnetic surfaces and the electric field producing conductor of this invention;

FIG. 3 is a partial cross-section of the electric field producing conductor of this invention and the means for positioning it in the endless discharge tube of FIG. 1;

FIG. 4 is a graphic representation of the confinement time of a heated plasma in the stellarator of FIG. 1 as a function of the voltage on the electric field producing conductor of this invention;

FIG. 5a is a graphic representation of the space potential vs. radius in the stellarator tube of FIG. 1 without an electric field imposed therein by the electric field producing conductor of this invention;

FIG. 5b is a graphic representation of the density profile vs. radius of a heated plasma in the stellarator tube of FIG. 1 without an electric field imposed therein by the electric field producing conductor of this invention;

2

FIG. 6a is a graphic representation of the space potential vs. radius in the stellarator tube of FIG. 1 with an electric field produced therein with the electric field producing conductor of this invention;

FIG. 6b is a graphic representation of the density profile vs. radius of a heated plasma in the stellarator tube of FIG. 1 with an electric field produced therein with the electric field producing conductor of this invention.

Referring now to FIG. 1, non-magnetic, bakeable, endless discharge tube 11 is stainless steel, except for ceramic portion 13, and forms an endless reaction chamber 15 inside the tube. A radial tubular duct such as duct 17, serves as an inlet into the chamber 15 for reactive gas from a suitable source (not shown), and for evacuation of chamber 15 to a high vacuum, e.g., 10^{-6} millimeters of mercury from a suitable source (not shown).

Advantageously, means such as an annular ferrite ring 19, disposed around tube 11, has an electrical winding 21 and a radio-frequency high electrical energy source (not shown) and operates to ionize gaseous atoms introduced into chamber 15. This produces a substantially neutrally charged plasma of ions and electrons in chamber 15. A suitable neutral plasma may, however, be injected directly into the chamber 15 through a suitable duct like duct 17.

Laminated iron annular ring 23, also disposed around tube 11, has suitable windings 25 and a suitable audio frequency, high electrical energy source (not shown), and operates ohmically to heat a central cylindrical column 27 or ring of plasma all around tube 11. Annular fixed aperture limiter 29, which, for example, has an aperture diameter of 40 mm. co-axial with a 50 mm. inside diameter of tube 11, reduces the size of the ohmic discharge to a cylindrical shape co-axial with the axis 31 of tube 11 and to a thickness corresponding with the inside diameter of the limiter 29. The diameter of the plasma column 27 in FIG. 1 across the center of tube 11, thus corresponds with the inside diameter of the aperture limiter 29.

Ion cyclotron resonance heating section 33 optionally may be additionally disposed around tube 11 to provide additional plasma heating by transferring energy to the plasma, e.g., by ion cyclotron heating. This energy may be thermalized by magnetic damping and to this end suitable axial windings are arranged to provide a magnetic field gradient.

Divertor 41, located in one of the straight sections 43 of tube 11 removes impurity ions from chamber 15 and to this end a suitable source (not shown) energizes suitable windings in the divertor to provide a local magnetic field in reaction chamber 15 which locally distorts the main axially confining magnetic field lines 45, described in more detail hereinafter. This causes the axial confining field lines near the wall of tube 11 to be bent into a chamber provided in the divertor and they are bent through parallel, non-magnetic metallic impurity-ion-collector plates in the divertor 41. Advantageously tube 11 also carries external heating elements (not shown) which bake tube 11 to high temperatures in excess of 400° C. for long periods of time to help remove impurity ions from tube 11 through the above-mentioned vacuum system for tube 11.

On its outside circumference, tube 11 has external axial magnetic field windings 51 all the way around tube 11, partially shown for ease of explanation, and associated external, oppositely, adjacently energized, helical windings 53 on both of the opposite end loops 57 of tube 11. Windings 51 and 53 advantageously both have the same electrical energy source, such as a high power direct current source (not shown) and this source operates with these windings 51 and 53 to establish a high strength axial magnetic field with a rotational transform around

the axis 31 of tube 11 in chamber 15. This high strength magnetic field, which may vary for various stellarator tube diameter sizes, for example, from a 38 kG field to a magnetic field of over 50 kG provides longitudinally extending magnetic lines of force 45 which form many cylindrical magnetic surfaces 59 co-axial with the axis 31 of tube 11, as illustrated for ease of explanation in FIG. 2 by only two surfaces 59 and 59'. Annular aperture limiter 29 has a hole diameter larger than the diameter of magnetic surface 59' (FIG. 2) which is described in more detail hereinafter.

The mentioned magnetic surfaces 59 produce an inward magnetic pressure greater than the outward plasma pressure and confine the plasma by impeding the outward movement of the plasma particles across these magnetic surfaces 59 to the inside wall of tube 11. Heretofore, the density gradient of the neutral plasma in tube 11 has been substantially uniform from the tube axis 31 to the inside of the tube 11. With a tungsten, flat, solid ring shaped, aperture limiter 29 inside tube 11, this density has been substantially uniform from the tube axis 31 to about 5 mm. from the inside wall in a 25 mm. radius tube 11 with an aperture limiter having a radius of 20 mm., as shown in FIG. 5b. As shown in FIG. 5a there has also been a very small, substantially uniform or flat space potential from the tube axis 31 to the inside diameter of the aperture limiter 29.

In accordance with this invention electrical conductor 61, having a large longitudinally extending, exposed area, is properly positioned by biasing it into heated plasma column 27, transversely of the axial magnetic field lines 45 in tube 11 and so as to intersect the conductor 61 with two or more magnetic surfaces such as inner and outer surfaces 59 and 59' as shown in FIG. 2. Advantageously, the biasing of conductor 61 is normal to the tube axis 31 in the plane of tube 11 in which straight sections 43 and end loops 57 are formed, but since the intersecting magnetic surfaces are cylindrical, the biasing may be at other angles than normally to the axis 31. Also this biasing may be in a plane intersecting the plane of the tube 11 and its end loops 57 at an angle. Source 63 impresses a large positive potential on conductor 61 from outside tube 11 and conductor 61 intersects at least two spaced magnetic surfaces such as magnetic surfaces 59 and 59' that instantaneously convey a large electron current flow to the conductor 61 from all around the tube 11. The conductor 61 draws a large electron current from the plasma in column 27 greatly to disturb the charge neutrality of this plasma all the way around tube 11 and produces an annular electric field region 65 in the whole outer region of the heated plasma column 27 from the free end 62 of conductor 61 outwardly. This internally imposed electric field interacts with the externally imposed axial magnetic field to rotate the portion of the plasma in heated plasma column 27 which contains this electric field region 65 whereby the confinement time of the plasma in heated column 27 is increased.

This confinement time is increased considerably as shown in FIG. 4, and since the plasma temperature increase will correspond to the confinement time increase, the plasma temperature also will be increased thus to increase the value of the plasma as a research tool. Also, this invention decreases the plasma diffusion coefficient without decreasing the thickness of the heated plasma column 29. Additionally, when increasing the temperature sufficiently, increased numbers of useful reaction products such as increased numbers of neutrons will be produced.

In order to understand the operation of this invention in a high strength magnetic field, reference is made to FIGS. 1 and 2. With a potential of several hundred volts positive on the conductor 61 with respect to the wall of discharge tube 11, a large electron current is drawn from the plasma. Then, because, a certain region of the plasma is starved of electrons, the electric potential of this

region rises. The charge neutrality of the plasma is thus purposely disturbed by drawing a large electron current from only one position on a magnetic shell extending between two magnetic surfaces 59 in chamber 15, and this raises the electric potential of the entire shell, all around the tube 11, and establishes a radial electric field in the whole outer region 65 of the cylindrical heated plasma in tube 11. This radial electric field acting with the axial magnetic confining field then causes the plasma to rotate with a vector velocity given by

$$\vec{V} = \frac{\vec{E} \times \vec{B}}{B^2}$$

where $\vec{E}$ =the vector radial electric field strength and $\vec{B}$ =the vector axial magnetic field strength. It is this rotation of the plasma in electric field region 65 of column 27, much faster than the loss rate of the plasma, which it is believed is responsible for decreasing the plasma loss rate by at least a factor of eight. Also, the plasma diffusing outwardly from the inner electric field free region of column 27 in tube 11, rapidly is rotated upon entering the electric field region 65 so as to delay its travel to the wall of tube 11.

In a practical arrangement for the apparatus of this invention reference is made to FIG. 3 which shows a 0.4 mm. diameter tungsten wire conductor 61 extending to about 3 mm. beyond the end of a 1.3 mm. outside diameter alumina tube 67. The ohmic transformer heating is induced parallel to the magnetic confining field by means of direct current source having a 400 kw. or higher power amplifier and the plasma loop voltage is programmed with control 69 to obtain a discharge of approximately constant conductivity. During this phase, which may last about 500 μ sec. or longer, the measurements illustrated in FIGS. 4, 5a, 5b, 6a and 6b were made.

Advantageously conductor 61 has around its annular insulator 67 a suitable metal support 71. Also it has a suitable vacuum tight means 73 for biasing the conductor 61 and suitably positioning it in the plasma in tube 11 at an angle to the tube axis 31. As shown in FIG. 3, this vacuum tight biasing and positioning means 73 comprises a duct 75 connected to tube 11 on the plane of the tube 11 and its end loops 57. This duct 75 has a flange 77, end plate closure 78 therefor and an annular array of bolts 79 for holding this closure in vacuum tight relation with flange 77. Closure 78 also connects and supports, in vacuum tight relation therewith, one end 81 of bellows 83. At the other end 85, bellows 83 has a vacuum face seal assembly 87 and the conductor 61, its insulator 67 and support 71 pass through the center of this face seal assembly 87 and glass cap 88 with glass-Kovar-metal seal 90, which are in vacuum tight relation to maintain the vacuum inside the bellows 83 that communicates with the vacuum in chamber 15. Conductor 61 passes through its insulator 67 the open end of its metal support 71, and a glass-tungsten press-seal in cap 88 therefor and past a metal yoke 89 without touching the yoke to positive potential source 63 while the conductor is electrically insulated from tube 11.

Flange 77 also carries a longitudinally extending metal support 93 that is slideably engageable with seal assembly 87 at end 85 of bellows 83. To this end triangular metal bridge 95 connects with seal assembly 87 and this triangular piece 95 passes through a suitable longitudinally extending slot in support 93. Also, this triangular piece 95 carries a sole plate 97 that normally holds the seal assembly from being lifted off the top of support 93.

Support 93 also carries a rotatable sleeve 99 having a threaded aperture 101 through which rod 103 threads for the inward and outward movement of seal assembly 87. Atmospheric pressure acting on the face seal assembly 87 creates a force inward toward tube 11 that is transmitted by way of yoke 89 to rod 103 and hence through aperture 101 to sleeve 99 such that sleeve 99 is held in con-

tact with the right angle extension plate 104 of support 93. By rotating sleeve 99 to move rod 103 inwardly toward tube 11, stationary rod 103 thrusts yoke 89 and seal assembly 87 inwardly along the top of support 93 and in line with the slot therein through which triangular bridge 95 passes. This biases conductor 61 inwardly. By reversing the rotation of sleeve 99 the rod 103 draws yoke 89 and its connection with seal assembly 87 outwardly, oppositely from tube 11 and this draws conductor 61 as well as its surrounding insulator 67 and support 71 outwardly from axis 31 in tube 11 in a line substantially normally to this axis 31 and in the plane of the tube 11 and its end loops 57.

Rod 103 also carries an inductor arm 105 that moves with rod 103 in relation to index 107 on stationary support 93. This index is scaled suitably to indicate the distance of conductor 61 from the center of tube 11 and thus the location of conductor 61 in chamber 15. Advantageously, a 0.4 mm. diameter conductor 61 with 3 mm. of the conductor 61 exposed beyond the end of its insulator 67 is positioned with the tip 62 of the conductor 61 10 mm. from the axis 31 of tube 11 in the heated plasma column 27.

With an exposed conductor 61 three mm. long at a radial position of 10 mm. and +200 v. the conductor 61 draws all the electron current that can diffuse into the magnetic surfaces 59 and 59' intercepted by the exposed tip 62 of conductor 61 without damage to conductor 61. Under these conditions the free charge distribution is shown in FIG. 6a by the dashed line 111 and the plasma density gradient is shown in FIG. 6b. As shown, the space potential of the plasma is uniform from the center of the discharge to the radius of the inducing probe and has a value under most conditions equal to or somewhat less than the potential of conductor 61. From the radius of conductor end 62 to the radius of the current channel 27, a more or less uniform electric field exists azimuthally symmetric about the magnetic axis 31 of the stellarator. The space potential at the edge of column 27 is approximately equal to 3.5 times the electron temperature measured in ev.

If, instead of operating this large collecting area conductor 61 at constant potential, a positive step voltage is impressed thereon, the conductor 61 current can be integrated to find the total charge needed to establish a given space potential V_s in stellarator tube 11. In this way it is suggested that the conductor 61 of this invention establishes a plasma capacitor having a magnetic surface 59 as the inner plate, the discharge tube 11 as the outer plate and the plasma therebetween as a dielectric with a dielectric constant

$$K = \frac{Q}{q} \times 200$$

Also, it has been found that the measured value of the radial electric field established by the conductor of this invention in a strong axial confining field, corresponds to a plasma rotation frequency of about 100 kc.

With regard to the diffusion of the plasma, the conductor 61 of this invention produces two regions in column 27 in which there are two different diffusion coefficients. In the inner region 112 of column 27, where there is substantially no radial electric field, the diffusion is represented by D_i . In the annular outer electric field region 65 of column 27, which surrounds the inner region 112 and where there is an average radial electric field of about 200 v./cm., the diffusion is represented by D_o . Although these diffusion coefficients are independent of plasma density, there is only a small density gradient observed in the inner region 112 and a much larger density gradient in the outer region 65. Also, these two density gradients are produced without decreasing the width of the heated plasma column 27.

The best fit to the experimental points is obtained for $D_i/D_o = 8$ and this ratio holds when moving the current drawing conductor 61 inwardly. Moving the conductor

end 62 into an inner magnetic surface (not shown), e.g., to a radial position of 8 mm. enlarges the outer region in which the radial electric field and a larger density gradient exists thus variably and adjustably to change the thickness of the inner and outer region 112 and 65 while maintaining the same large diameter of heated plasma column 27.

In FIG. 4 the plasma confinement time T_c is plotted as a function of the voltage on a 3 mm. conductor whose end 62 is located at a radial position of 12 mm. with a constant conductivity plasma; the confinement time is lengthened by a factor of 1.9 or longer from that known heretofore, as the voltage on the conductor is raised to about 200 v. positive. In contrast to the constant diffusion of the plasma known heretofore where the diffusion coefficient has been 2.1×10^3 cm.²/sec. or more for a 4 ev. plasma in a 38 kG field the diffusion coefficient in the outer region with this invention, actually has been reduced to 1.3×10^3 cm.²/sec. or less. Also in contrast to the rather flat density profile when no radial electric field is applied, the density increases from the tube wall to the interior of the plasma in the presence of the applied radial field.

If the potential of the inducing conductor 61 is varied and the current to this conductor i_p is plotted as a function of the space potential of the plasma at the radius of the inducing conductor V_s , we find

$$i_p \sim \frac{n_e V_s}{B^3}$$

where n_e is the density, and B is the magnetic confining field. This relationship holds for values of V_s from approximately +200 volts to a value of about +300 volts.

In the actual operation of the conductor 61 of FIG. 3 the effects discussed above have been observed while the conductor 61 remained stable under the following advantageous actual conditions:

Plasma conditions (fully ionized hydrogen plasma):

Electron density, $10^{13}/\text{cm.}^3$

Electron temperature (conductivity), 4 ev.-5 ev.

Plasma diameter, 50 mm.

Magnetic field, 38 kilogauss

Rotation in electric field region 65 about 100,000 revolutions/sec.

Conductor dimensions (tungsten wire):

Diameter, 0.4 mm.

exposed portion in plasma, 3 mm.

Ceramic tube, 1.3 mm. diameter

Conductor end, 10 mm. from center of plasma discharge

Conductor potential, +200 v. with respect to discharge tube 11

Conductor current, about 0.6 amp.

Radial electric field 65: Cylindrical symmetry with respect to the plasma axis annular all around tube 11 between radial position 13 mm. and 25 mm. from axis 31 of tube 11.

Plasma loss: 1.3×10^3 cm.²/sec. (for 4 ev. plasma)

In the region 65 having an imposed radial electric field the diffusion coefficient is 1.3×10^3 cm.²/sec. for 4 ev. plasma. This is at least 8 times less than the loss rate in region 112 having no imposed radial electric field.

Reduced loss rate persists typically for duration of discharge which is up to 1 millisecond or more.

In other tests the high conductor potential of at least +200 v. was applied with plasma densities up to 3×10^{13} , temperatures up to 25 ev., and magnetic fields up to 40 kG without any damage to the conductor 61 and without any significant change in the conductivity of the plasma at any point across the diameter of plasma column 27. In all these tests, the probe was capable of collecting more electrons than could be supplied readily by the plasma and to this end the current of conductor 61 was maintained close to the saturation electron current. Thus,

assuming that the electrons were supplied from the shell defined by the magnetic surfaces intercepted by the exposed conductor 61, then the flow of electrons into this shell was less than the saturation electron current.

In order to set an analytical expression for this latter inequality, assumptions are made about the type of diffusion taking place and the density gradients existing in the plasma. A rough model, assuming "pumpout" is a diffusion process that goes as T_e/B , leads to the expression

$$\frac{T_e^{1/2}r}{Ba} < \text{const.}$$

where T_e is the electron temperature, B is the magnetic field, r is the radius of the conductor end, and a is the collecting area of the probe. Observations so far fit this model qualitatively.

Actual tests have also shown that the conductor of this invention provides confinement time that increases with the square of the magnetic confining field and also increases with the electron temperature. This is entirely different from the confinement shown in stellarators heretofore.

The conductor of this invention and the electric field produced thereby makes the ohmically heated stellarator a more useful device for plasma physics experiments and at sufficiently high temperatures for increased reaction products therefrom. Also, the heretofore known high "pump-out" diffusion has, at least in part, been nullified by this invention. The confinement time has been shown to be increased at least two-fold with this invention and with increased magnetic confining fields and increased stellarator sizes this increase in confinement will be even greater. This invention also will provide plasma confinement such as is necessary in realizing an economical thermonuclear reactor and to this end this invention may be used for igniting the plasma in a full scale controlled thermonuclear reactor.

What is claimed is:

1. In a method for increasing the confinement time of a high temperature plasma in a stellarator having confining coils which produce an axial magnetic field including axial field lines forming cylindrical magnetic surfaces for magnetically confining the plasma, an evacuated metallic endless tube inside said coils, means for providing in said tube a cylindrical neutrally charged plasma of ions and electrons, and means for ohmically heating to high temperature a column of said plasma which said magnetic field confines in said tube along the axis of said tube while said hot plasma column is being heated to a high temperature, the improvement comprising withdrawing large numbers of electrons in a direct flow from said plasma in said tube through a thick positively charged conductor having a free exposed end, said end being within said column thereby to disturb the space charge neutrality of said plasma sufficiently to establish an annular radial electric field region from said free end of said conductor outwardly, said electric field interacting with said axial magnetic field produced by said coils to cause said plasma in said electric field region to rotate rapidly around said stellarator thereby to increase the confinement time of said plasma in said high temperature column of said plasma, and moving said conductor for controlling said electric field region thickness.

2. A method for increasing the confinement time of a high temperature plasma in a stellarator having confining coils which produce an axial magnetic field including axial field lines forming cylindrical magnetic surfaces for magnetically confining the plasma, an evacuated metallic endless tube inside said coils, means for providing in said tube a cylindrical neutrally charged plasma of ions and electrons, and means for ohmically heating to high temperature a column of said plasma which said magnetic field confines in said tube along the axis of said tube while said plasma column is being heated to high temperature,

comprising withdrawing large numbers of electrons in a direct flow from said plasma in said tube through a single, thick, exposed, positively charged, free, conductor end positioned within said plasma to disturb the charge neutrality of said plasma sufficiently to establish an endless, annular, radial electric field region from said free conductor end outwardly which interacts with said axial magnetic field produced by said coils to cause said plasma in said electric field region to rotate rapidly around said stellarator thereby to increase the confinement time and temperature of said plasma in said high temperature column of plasma, and moving said conductor in a direction to increase the thickness of said electric field region.

3. The invention of claim 1 in which said exposed free conductor end is about half way into said plasma column and produces an inner first plasma diffusion zone, column half way across said plasma column and an outer annular cylindrical second plasma diffusion zone across the remaining half of said plasma column, said plasma diffusion being slower across said second zone than across said first zone toward said tube wall, and wherein said conductor is moved away from the center of said hot plasma column to remove said conductor away from said hot plasma column.

4. In a stellarator having confining coils which produce an axial magnetic field for magnetically confining a high temperature plasma, an evacuated metallic endless tube inside said coils, and means for providing in said tube a cylindrical column of hot ionized plasma which said coils confine in said tube along the axis of said tube, a rotating plasma means, comprising a positive source of potential having a high value relative to said tube, a conductor in said plasma column having an exposed conductor end and means for insulating said conductor from said tube, means for biasing said conductor at an angle to the tube axis to connect said plasma to said source of potential from only one position in said plasma, said conductor being so positive as to deplete said plasma of electrons adjacent said conductor with a current flow in said conductor sufficient to draw electrons from all around the stellarator, said flow of electrons establishing an annular cylindrical radial electric field in hot ionized plasma from said conductor end to the outside of said plasma column, said electric field being in operable association with said magnetic field produced by said coils for causing said electron depleted plasma to rotate rapidly around said stellarator thereby to increase the confinement time and temperature of the plasma in said hot ionized column.

5. In a stellarator having confining coils which produce an axial magnetic field having axial field lines forming cylindrical magnetic surfaces for confining a high temperature plasma, an evacuated metal endless tube inside said coils, an annular aperture limiter, and means for providing a column of hot ionized plasma inside said aperture limiter which said coils confine in said tube along the axis of said tube, a rotating plasma means, comprising a positive source of potential which is high in value relative to said tube, a conductor having an exposed end extending longitudinally into said tube at an angle to said tube axis so as to intercept several of said magnetic surfaces, means for selectively biasing said conductor end into said column of hot ionized plasma, said conductor end having a large cross-sectional area for drawing all the electron current that can diffuse into said magnetic surfaces intercepted by said exposed conductor end, said conductor drawing all this electron current from said plasma to produce an annular positive, radial, space potential relative to said tube from the exposed conductor end to the inside diameter of said tube along the axis of said tube and a corresponding annular electric field, said electric field and magnetic field being in operable association rapidly to rotate said plasma around the axis of said tube whereby the confinement time and temperature of said plasma are increased.

6. In a stellarator having confining coils which produce an axial magnetic field of at least 38 kilogauss for magnetically confining a high temperature plasma, an evacuated metal endless tube inside said coils, means for providing in said tube a cylindrical plasma having an electron density of at least $10^{13}/\text{cm.}^3$, an electron temperature conductivity of 5 ev., a plasma diameter of at least 50 mm., and means for providing a column of hot ionized plasma which said coils confine in said tube along the axis of said tube, a rotating plasma means, comprising a positive source of potential having a 200 v. positive potential relative to said tube, a conductor having an exposed end extending transversely into said tube at an angle to the axis of said tube, means for selectively biasing said conductor end to about 10 mm. from the center of said column of hot ionized plasma, said end of said conductor having a cross-sectional diameter of about 0.4 mm., and removing large numbers of electrons from said plasma at a current of about 0.6 ampere, said conductor current producing a positive radial plasma space potential relative to said tube from said exposed conductor end to the outside of said column of hot ionized plasma and a corresponding radial electric field region having a cylindrical symmetry with respect to the axis of said tube all around said stellarator, said electric field being in operable association with said magnetic field produced by said coils rapidly to rotate said plasma in said electric field region around the stellarator at a speed of about 100,000 revolutions per second whereby the confinement time and temperature of the plasma column is increased.

7. Means for producing an annular rotating plasma of variably adjustable thickness, comprising means for producing an ohmically heated column of hot ionized plasma, an endless evacuated metal shell surrounding said plasma and having coils supported on the outside of said shell for producing an axial magnetic plasma confining field with a rotational transform inside said shell, an exposed conductor end having means for maintaining said conductor end positively charged with respect to said metal shell, and means for variably adjustably biasing said conductor end transversely to said magnetic field and positioning it deeply into said column of hot ionized plasma so that there is a direct flow of electrons to said conductor from

said plasma that produces an outer annular electric field in said plasma column around the length of the metal shell, said electric field operating with said magnetic field rapidly to rotate the plasma in said electric field, the thickness of said rotating plasma corresponding to the depth to which said conductor end is positioned into said column of hot ionized plasma.

8. Means for producing an annular rotating plasma of variably adjustable thickness, comprising means for producing an ohmically heated column of hot ionized plasma, an endless evacuated metal shell surrounding said plasma and having coils supported on the outside of said shell for producing an axial magnetic plasma confining field with a rotational transform inside said shell, an exposed conductor end having means for maintaining a high positive potential on said exposed conductor end with respect to said metal shell, means for variably adjustably biasing said exposed conductor end transversely to said axial magnetic field so as to position it deeply into said column of hot ionized plasma whereby said magnetic field rapidly transports plasma electrons to said conductor from around the length of said metal shell and produces an outer annular electric field region around an inner electric field free region in said column of hot ionized plasma, said plasma in said electric field region interacting with said axial magnetic field rapidly to rotate the plasma in said annular electric field region, and means for indicating the position of said exposed conductor end with respect to the center of said column of hot ionized plasma whereby the thickness of said rotating plasma is selectively adjustable with respect to said exposed conductor end.
